HER ATTORNEY

UNITED STATES PATENT OFFICE

CATHERINE C. KULP, OF PHILADELPHIA, PENNSYLVANIA

CLASP

Application filed March 11, 1931. Serial No. 521,691.

This invention relates to clasps, and has for an object to provide an improved type of clasp especially adapted to hold the extended or loose end of a belt.

5 A further object of the invention is to provide a clasp of the type having an improved type of torsional spring for effecting the clamping action.

The invention comprises hinged leaves 10 properly proportioned to engage upon the opposite sides of a belt, and the extended end associated therewith, and with a pintle for the hinge so connected as to provide torsional resistance to the separating of the 15 leaves.

The invention is directed to other objects and possesses other features of novelty and advantage, some of which, together with the foregoing, will be hereinafter more fully set 20 forth.

In the drawings:

Figure 1 is a view in front elevation of the improved clasp in operative position,

25 Figure 2 is an enlarged detail view of the clamp in elevation,

Figure 3 is a view of the clasp in edge elevation, as indicated by arrow 3, at Figure 2,

30 Figure 4 is a sectional view of the clasp as indicated by the line 4-4 at Figure 3, and

Figure 5 is a sectional view of the clasp as indicated by the line 5-5 at Figure 2.

Like characters of reference indicate corresponding parts throughout the several views.

35 The improved clasp, which forms the subject matter of this application, comprises a leaf 10, properly contoured to some artistic configuration to appear as the front of the clasp when in operative position, as shown at Figure 1.

The leaf 10 is bent to form a section 11 spaced from and parallel with the leaf 10. As shown in the drawings, this is provided by a right angularly disposed section 12, but it is to be understood that the angles as herein illustrated are unimportant, and that other angles may be substituted, or curves instead of angles may be substituted.

40 A second leaf 13 is hinged to the section 11 by means of a pintle 14 which extends through

a roll 15 on the leaf 13 and through ears 16 on the section 11. This pintle 14 is then bent as at 17 and 18 with sections 19 and 20 extending transversely across the leaves 13 and the section 11, respectively.

45 The section 19 is engaged by ears 21 and 22 formed integral with the leaf 13, and the section 20 embraced by the roll 23 on the section 11.

When the leaf 13 is moved to dotted position is shown at 13' in Figure 3, the pintle 14 is placed under torsional stress which returns the parts to normal position when released. The leaves may, therefore, be separated by moving the leaf 13, as indicated, and in that position, the device slipped over the contacting edges of the belt and belt end as shown at Figure 1. When released, the leaf 13 will engage the inner side of the belt while the leaf 10 will engage the front and hold the extended end of the belt in position.

50 Of course, the clasp, herein illustrated, may be modified in various ways without departing from the invention herein set forth and hereinafter claimed.

75 The invention is hereby claimed as follows:

1. A clasp embodying an integral spring having three substantially parallel sections joined by end sections, a leaf having end loops 80 embracing the intermediate section and a central loop embracing one remote section and a second leaf having end loops embracing the other remote section, and a central loop embracing the intermediate section. 85

2. A clasp embodying an integral spring having three substantially parallel sections joined by end sections, a leaf having end loops embracing the intermediate section and a central loop embracing one remote section and a 90 second leaf having end loops embracing the other remote sections, and a central loop embracing the intermediate section and interlying the end loops of the other leaf.

3. A clasp embodying an integral spring 95 having three substantially parallel sections joined by end sections, a leaf having end loops embracing the intermediate section and a central loop embracing one remote section and a second leaf having end loops embracing 100

the other remote sections, and a central loop embracing the intermediate section and inter-
lying the end loops of the other leaf, said
leaves being contoured for clamping interac-
tion.

⁵ In testimony whereof I have signed my
name to this specification.

CATHERINE C. KULP.
